OBADIAH B. BROWN, OF MALDEN, MASSACHUSETTS.

Letters Patent No. 76,886, dated April 21, 1868.

TOY BOOMERANG PISTOL.

The Schedule referred to in these Letters Patent and making part of the same.

TO ALL WHOM IT MAY CONCERN:

Be it known that I, OBADIAH B. BROWN, of Malden, in the county of Middlesex, and State of Massachusetts, have invented a new toy, which I designate as a Boomerang Pistol; and I do hereby declare the following to be a full and correct description of the same, reference being had to the accompanying drawings, in which—

Figure 1 is a perspective view of the upper side of the instrument, the boomerang being shown in place, and the spring retracted ready for use.

Figure 2 is a similar view of the bottom of the instrument, showing the arrangement of the spring. The same part is marked by the same letter in both figures.

This invention consists of an instrument to hold and project a toy boomerang, which I denominate a boomerang pistol, and which forms a novel and amusing toy for children.

In the drawing, A marks the flat piece of wood on which the boomerang is to be laid; B, the handle; C, a cleat placed across the piece A for the boomerang to lie against; D, the boomerang, which may be made of one or more pieces of thin veneering, or of a thin piece of hard rubber; E, the spring from which the projectile force is obtained. The fixed end of this spring is attached to the lower side of piece A by a screw at a. It is then passed in a coil twice around the shank of the button F, and brought out to the edge of A, and its free end turned up, as shown. A roll of rubber is attached to the turned-up end of the spring, and comes in contact with the boomerang when the blow is struck. It serves as a cushion to prevent the wear of the boomerang, which would occur if it were struck directly by the metallic spring. G is a catch which holds the spring retracted until it is pressed down and released.

The operation is as follows: The boomerang D is placed in position, as shown in fig. 1, and the spring E retracted and held by the catch G. The end of spring E is then pressed down by the thumb of the holder until the spring is released and flies forward, giving the requisite impulse to the projectile.

Having thus described my invention, what I claim, and desire to secure by Letters Patent, is—

The toy herein described, consisting of an instrument for supporting and throwing a small boomerang, constructed and operating substantially as described.

The above specification of my said invention signed and witnessed at Boston, this 23d day of November, A. D. 1867.
